UNITED STATES PATENT OFFICE.

SAMUEL H. CREIGHTON, OF INDIANAPOLIS, INDIANA.

HEATER FOR AUTOMOBILES.

1,359,490.

Specification of Letters Patent. Patented Nov. 23, 1920.

Application filed September 25, 1918. Serial No. 255,628.

To all whom it may concern:

Be it known that I, SAMUEL H. CREIGHTON, a citizen of the United States, and a resident of Indianapolis, county of Marion, 5 and State of Indiana, have invented a certain new and useful Heater for Automobiles; and I do hereby declare that the following is a full, clear, and exact description thereof, reference being had to the accompanying drawings, in which like numerals refer to like parts.

The object of this invention is the improvement of heaters or foot warmers for automobiles, aeroplanes and other vehicles 15 which are heated from the exhaust of the engine.

One feature of the invention consists in a heater formed of three metal elements or plates and a fire proof sheet of insulating 20 material upon the top of the base or bottom plate, the intermediate plate separating the air and heat chambers and being bent or grooved to form, in association with the bottom plate, conduits for the passage of the 25 heated gas and to form a relatively great heating surface. Said intermediate plate is grooved longitudinally of the heater between the sides of the conduit to present a relatively great amount of surface to the 30 heat in said conduit to make the heater act quickly and be effective.

Another feature of the invention consists in the formation of the heater by a plurality of layers of plates with a fire 35 proof sheet of insulating material lining for the base or bottom plate, the edges of said plates being secured together air tight and preferably by the edge of one plate over-lapping and being tightly crimped or 40 welded into engagement with the edges of the other plates.

Another feature of the invention consists in perforating the sides of the heater and the top thereof so that air will enter through 45 the side openings and carry air through the top openings and prevent any pocket or dead chamber where the air or the like ceases to circulate or move. With this device a constant circulation of air coming 50 out of the top of the device is maintained automatically.

The foregoing and other novel features of this invention will be understood from the accompanying drawings, the following 55 description and claims:

In the drawing Figure 1 is a perspective

view of a portion of the interior of an automobile body showing the heater and associated parts in place, parts being broken away. 60

Fig. 2 is a perspective view of the heater and associated parts, parts being broken away.

Fig. 3 is a transverse section through the heater on the line 3—3 of Fig. 2. 65

Fig. 4 is a transverse section through the heater on the line 4—4 of Fig. 3.

A part of an automobile body 10 is shown in Fig. 1 with the heater 11 in place on the heel board of the seat, but it is understood 70 that said heater can be placed on the toe board or on the floor or built in the floor, if desired. The heater 11 is supplied with heated gas through the flexible tube 12 which leads from the exhaust pipe 13 of the engine, not shown, of the automobile. When the heater is in operation the heated gas is deflected from the exhaust pipe 13 through the tube 12 and heater 11. 75

The construction of the heater is indicated 80 in Figs. 2, 3 and 4. It is made of sheet metal elements or plates forming the top 15 the bottom 16 and intermediate plate 17 and the inner surface of the bottom plate 16 is lined with a sheet of heat insulating material 18. 85 The bottom plate is flat as is also the sheet of insulating material 18 and they extend the full width of the heater. The intermediate sheet 17 is of the same width and length as the other parts but is crimped to form the 90 grooves or passages shown and hereinafter explained. Its lateral portions extend down and lie flat upon the edges of the plates 18 and 16. The top plate is the shape of an inverted pan, the body of it lying above the 95 intermediate portion and out of contact, and the lateral portions extend down to form a compartment and the edge is U-shaped to form a bead which surrounds, overlaps and clamps or crimps the edges of all other 100 plates tightly together so as to make a gas tight joint, the member 18 serving as a gasket or packing.

With this construction there is a gas chamber 20 between the intermediate plate and 105 the bottom plate and a hot air chamber 21 between the intermediate plate and the top plate. There are perforations 22 in the top of the top plate for the outlet of the heated air and there are perforations 23 in the side 110 walls of the top plate through which air is admitted into the heating chamber. The

outside air enters the chamber 21 through the side perforations 23 and is heated by the intermediate plate 17 and then passes up through the outlet openings 22. Without 5 the side openings 23, the hot air chamber 21 is, to a great degree dead, as there is nothing to create currents of air through it to be heated in their passage.

The intermediate plate 17, which heats the 10 air in air chamber 21, is so formed as to have a relatively great surface both for receiving heat on the under side and transmitting heat on the upper side thereof, and it is so formed in combination with the bottom of the heater 15 that it forms a tortuous conduit from the supply pipe 12 to the outlet 25. These two objects are accomplished by bending the intermediate plate so as to form large ribs 30 which engage the bottom of the chamber so 20 as to form the tortuous conduit 31 as seen in Fig. 4, leading from the inlet 12 to the other end of the device and back to the first named end and then to the outlet 25. But to still further increase the heating surface, the 25 intermediate plate is wrinkled down longitudinally to form the downwardly extending ribs 32 and which extend about half way from the intermediate plate to the bottom of the heating chamber, and intermediate 30 the sides of the conduit 31 so as to form a double conduit as shown in Figs. 2 and 3. The right hand rib 30 shown in Fig. 3 does not extend entirely to the end of the heater and the left hand rib 30 does not extend en- 35 tirely to the other end of the heater so as to leave transverse openings to make the conduit 31 as shown in Fig. 4. One outside rib 32 does not extend entirely to the end of the heater where the inlet 12 is located and the 40 other outside rib 32 does not extend entirely to the other end of the heater at the outlet 25 so as to leave small chambers at the inlet and outlet. The bottom wall of the heating chamber is formed of insulating material 45 18 so that the bottom 16 is not heated and no heat is lost.

When it is desired to use the heater the cable 40 is pulled, it extending from the bracket 41 on the seat, around the pulley 42 50 connected with the exhaust pipe 13, to a valve lever 43 which controls a valve (not shown) in the tubular neck 43^a which receives the end of the tube 12 adjacent the heater, so as to open said valve. The valve is closed by 55 the spring 44 which extends from the valve lever 43 to a collar 45 on the pipe 13.

To enable the valve to be attached to pipes 13 of various diameters the tubular neck 43^a to which the end of tube 12 is connected is 60 carried by a clamp 46 which surrounds the tube 13 and has two long ears 47 that are brought together and secured by a bolt 48. These ears have a number of holes or slots 49 in them so that the clamp will be adaptable 65 to pipes of various sizes. The pipe 13 has a

hole in it, not shown, which communicates with the tube 12 through the neck 43^a.

The foregoing explains what is deemed to be the preferred form of said invention as to details, but the invention is not intended 70 to be limited to such details.

The invention claimed is:

1. A heater of the character described 75 formed of top and bottom outside plates arranged to form a compartment and an intermediate plate separating the compartment into a heating chamber and a hot air chamber, the intermediate plate having ribs for forming a circuitous passage through the heater, one of said outside plates having 80 its edge overlapping and crimping or clamping the edges of the other plates for crimping or clamping the edges of the plates together in an air tight joint.

2. A heater of the character described 85 formed of top and bottom outside plates arranged to form a compartment and an intermediate plate separating the compartment into a heating chamber and a hot air chamber, the intermediate plate having ribs for 90 forming a circuitous passage through the heater, and a sheet of insulating material lining the bottom plate, the edge of one of said outside plates overlapping and crimping or clamping together the edges of the 95 other plates and the sheet of insulating material to form an air tight joint.

3. A heater of the class described including top and bottom members arranged to 100 form a compartment and an intermediate plate for separating said compartment into a heating chamber and a hot air chamber, said intermediate plate having longitudinally extending ribs engaging the bottom members, the alternate ends of said ribs 105 terminating a distance from the edges of the intermediate plate to provide openings for forming a tortuous conduit in the heating chamber for the passage of heating elements through the chamber.

4. A heater of the class described including top and bottom members forming a compartment and an intermediate plate for separating the compartment into a heating chamber and a hot air chamber, said intermediate plate having longitudinal depressions for forming a conduit and additional depressions intermediate the conduit forming depressions for increasing the heating surface of said intermediate plate.

5. A heater of the class described including top and bottom members arranged to form a compartment, and an intermediate plate for separating said compartment into a heating chamber and a hot air chamber, said 125 intermediate plate having depressed portions for forming a conduit, the depressed portions adjacent opposite ends of the plate being omitted for forming passages for the heating element.

6. A heater of the class described including top and bottom members and an intermediate plate for separating the space between the top and bottom members into a heating chamber and a hot air chamber, portions of said intermediate plate being depressed to form ribs, said intermediate plate having additional depressions of less depth than the depressions forming the ribs for increasing the heating capacity of the conduit formed by the ribs. 15
- 5 7. A heater of the class described including top and bottom members and an intermediate plate for separating the space be- 20
- 10 tween the top and bottom members into a heating chamber and a hot air chamber, said plate being preferably formed of sheet metal and having parts thereof bent downwardly longitudinally of the plate to form ribs, which ribs rest upon the bottom member and divide the heating chamber into conduits, said intermediate plate having other depressions of less depth than the depressions formed by the ribs for increasing the heating capacity of the heating chamber. 25

In witness whereof I have hereunto affixed my signature.

SAMUEL H. CREIGHTON.
